OF ROSETO, PENNSYLVANIA

AUTOMATIC GAS-STOVE LIGHTER

Application filed January 4, 1929. Serial No. 330,342.

This invention relates to an automatic gas stove lighter, the general object of the invention being to provide means for opening the cock of the pilot burner at the same time a 5 cock of one of the main burners is opened so that the projected flame from the pilot burner will light the gas at the main burner.

Another object of the invention is to so arrange the parts that the pilot burner cock 10 will be opened when any of the main cocks are opened and said pilot cock will be closed as soon as the main cock has been moved to fully opened position so that the full supply of gas to the pilot burner continues just long 15 enough to light the gas at the main burner.

This invention also consists in certain other features of construction and in the combination and arrangement of the several parts, to be hereinafter fully described, illustrated in the accompanying drawings and 20 specifically pointed out in the appended claims.

In describing the invention in detail, reference will be had to the accompanying drawings wherein like characters denote like or corresponding parts throughout the several views, and in which:—

Figure 1 is a plan view of the gas stove, showing the invention applied thereto.

Figure 2 is a front view of the stove, with 30 the invention applied thereto.

Figure 3 is a section on line 3—3 of Figure 1.

Figure 4 is a section on line 4—4 of Figure 1.

Figure 5 is a section on line 5—5 of Figure 1.

Figure 6 is a detail view of a modification.

In these drawings, the numeral 1 indicates 40 the main burners of the stove and 2 the pilot burner thereof, the main burners being connected by the pipes 3 with the supply pipe 4, the ordinary cocks 5 being placed in the pipes 3 for controlling the supply of gas to 45 the main burners. A pipe 6 connects the pilot

burner 2 with the supply pipe and a valve, operated by a pushbutton 8, controls the supply of gas to this burner. As is well-known, this valve is so constructed that a small quantity of gas will be supplied to the burner 2 at all times so that a small flame will occur at said burner, but when the pushbutton is depressed, a full supply of gas will be delivered to the burner 2 and this burner is so constructed that this increased supply of gas will result in flames being projected toward the main burners so as to light the gas at these main burners. As before stated, it is the object of our invention to provide means whereby this pushbutton is depressed automatically by the opening of one of the main cocks 5.

In carrying out our invention, we arrange a bar 9 adjacent the main cocks 5, this bar being slidably supported by the braces 10 which support the front part of the supply pipe 4 from the stove. A threaded member 10' is placed in a threaded hole in one end of the bar 9 and said member is formed with an L-shaped part 11 which engages the pushbutton 8 and the spring of this button acts to hold the bar in one limit of its movement.

The bar is provided with a number of vertically arranged openings 12 in each of which is pivotally arranged a clip 13 and a spring 75 plate 14 is fastened to the under side of the bar and covers the bottom part of each opening. This spring plate engages a projecting part of each clip and tends to hold the upper part of the clip projected above the top of 80 the bar.

A cam 15 is fastened to the movable part of each main cock, with the heel of the cam normally engaging the clip, but when a main cock is moved to open position, the curved 85 part of the cam will engage the clip and thus force the clip to the right, which, of course, causes the bar to also move to the right so that the button 8 is depressed and thus a full supply of gas will pass to the burner 2. As the 90

cock 5 is moved to its fully open position, the end of the cam will pass the clip so that the spring or button 8 will return the bar and the parts associated therewith to their normal position and at the same time the spring will close the valve of burner 2. When a main cock is closed, the cam will slide over the clip, thus depressing the same against the action of its spring 14 and as soon as the cam passes the clip, the spring 14 will return the clip to raised position and thus the parts will be set ready for the next opening movement of the main cock. Where a pushbutton is arranged at the center of the front of the stove, I provide a yoke-shaped part 11' at the center of the bar 9' which has a depending part 11'' for engaging the pushbutton when the bar is moved to the right.

From the foregoing it will be seen that we have provided simple means whereby the pushbutton valve is operated upon the opening of a main cock so that the lighter burner will be supplied with gas and the resultant flame will light the main burner. This action is wholly automatic and takes place on the opening of the main cock. As soon as the main cock reaches fully open position, the parts return to normal position and the full supply of gas to the lighter burner is cut off. The main cocks are moved to closed position without affecting the device.

It is thought from the foregoing description that the advantages and novel features of the invention will be readily apparent. It is to be understood that changes may be made in the construction and in the combination and arrangement of the several parts, provided that such changes fall within the scope of the appended claims.

What we claim is:

1. In combination with a gas stove including a lighter burner and its spring actuated valve, a member slidably arranged at the front of the stove and having a part engaging the valve, pivoted clips carried by said member and cams on the main cocks of the stove whereby when the cocks are moved to open position, the cams will engage said clips and move said member to cause the part thereon to open the valve, said cams passing beyond the clips when the cocks are moved to fully open position whereby the spring on the valve will return the parts to normal position and spring means for normally holding the clips in raised position.
2. In combination with a gas stove provided with a pilot burner having a pushbutton valve and a spring for holding the valve closed, a bar slidably arranged at the front of the stove and having vertically arranged openings therein, a clip pivoted in each opening, a spring engaging each clip and holding the same projected above the top of the bar, each main burner of the stove having a cock, a cam connected with each cock, said cams engaging

the clips on the opening movement of the cocks for moving the bar in one direction, the springs permitting the clips to lower when the cocks are moved to closed position and the cams pass over the clips and a part on the bar engaging the pushbutton of the valve whereby the valve is opened when the bar is moved by the opening movement of a main cock, the spring of the pushbutton acting to hold the parts in normal position.

In testimony whereof we affix our signatures.

GIUSEPPE RUGGIERO.
JOHN DE CESARE.
